[57] **CLAIM**

The ornamental design for a socket cover for electrical computer cables, as shown and described.

DESCRIPTION

FIG. 1 is a front elevational view of a socket cover for electrical computer cables showing my new design; FIG. 2 is a side elevational view thereof, the opposite side being a mirror image;

FIG. 3 is a cross-sectional view thereof, taken on line 3—3 of FIG. 1;

FIG. 4 is a rear elevational view thereof;

FIG. 5 is a top plan view thereof;

FIG. 6 is a bottom plan view thereof; and,

FIG. 7 is a perspective view thereof.
